Coloplast A/S; Nick Baumann(57) **CLAIM**

The ornamental design for an absorbent wound dressing, as shown and described.

DESCRIPTION

FIG. 1 is an isometric view of an absorbent wound dressing; FIG. 2 a top side view thereof; FIG. 3 is a bottom side view thereof; FIG. 4 is a front side view thereof, where a back side view is not illustrated as it is a mirror image of the front side view; and, FIG. 5 is a right side view thereof, where a left side view is not illustrated as it is a mirror image of the right side view. In FIGS. 1 and 3–5 the broken lines show portions of an absorbent wound dressing that form no part of the claimed design.
